UNITED STATES PATENT OFFICE.

FRED RICKS, OF LEICESTER, ENGLAND, ASSIGNOR TO UNITED SHOE MACHINERY CORPORATION, OF PATERSON, NEW JERSEY, A CORPORATION OF NEW JERSEY.

MACHINE FOR INCORPORATING STIFFENERS IN BOOTS AND SHOES.

Application filed August 10, 1925, Serial No. 49,307, and in Great Britain September 12, 1924.

This invention relates to machines for placing and for pressing into place in the uppers of boots and shoes, preparatory to the pulling-over and lasting operations, stiffeners which require some preliminary treatment such as dipping them in a solvent or subjecting them to heat in order to render them sticky and pliable.

Box-toe blanks of this general type are commonly incorporated in the uppers of boots and shoes in two ways (1) by stitching or stapling them in place and (2) by putting them loosely into the upper and depending upon their sticky quality when softened and upon pressure to fix them in position in the upper, the present invention being concerned with a machine for use in carrying out the last-named procedure. For example, a thermoplastic box-toe blank in its stiff condition is commonly placed in position between the proper layers of material at the toe portion of the upper, and then said toe portion, with the blank in place, subjected to the action of a heated press whereby the blank is softened by the heat and pressed into the layers of the upper to fix it in place. A machine for accomplishing the heating and pressing operations is disclosed in United States Letters Patent No. 1,443,378, granted Jan. 30, 1923, upon an application filed in the name of Ordway, said machine being adapted for use only with uppers before they are assembled upon lasts.

In incorporating a box toe blank in an upper in the manner which has been described above, the operator works at a disadvantage by reason of the fact that, in inserting the box-toe blank in the upper preparatory to the pressing operation, he must do three things at the same time, namely hold the upper down upon a table or other support, pull back certain layers at the toe portion of the upper and insert the box-toe blank in position.

According to the present invention, there are provided upper supporting means for facilitating the insertion of the stiffener and means for pressing the inserted stiffener into place, whether the upper is on or off the last. The pressing means may be heated, as in the machine of the patent; or, if desired, the

pressing means may be cold, and the stiffener rendered soft and sticky prior to the presentation of the upper with its stiffener to the pressing means. In any event, however, whether the stiffener is inserted in the upper in a stiff or in a soft condition, the insertion is greatly facilitated by the fact that the upper, whether on or off the last, is supported in such manner that the operator has both hands free to manipulate the layers of material of the upper and to insert the stiffener between the proper layers.

This and other features of the invention including certain details of construction and combinations of parts will be described as embodied in an illustrative machine and pointed out in the appended claims.

Referring now to the accompanying drawings:—

Figure 1 shows in side elevation a machine, according to the invention, for supporting an upper assembled upon a last to facilitate the insertion of a box-toe blank, and having means for pressing the toe portion of the upper;

Figure 2 shows diagrammatically on an enlarged scale a portion of materials of an upper supported by the machine of Figure 1 at a certain stage in a preferred way of using the machine;

Figure 3 shows in side elevation another form of machine according to the invention; and

Figure 4 is a plan view of the machine shown in Fig. 3.

The machine shown in Figure 1 has means for supporting an upper whether on or off the last in such manner as to leave both hands of an operator free to manipulate the toe portion of the upper while he inserts a box-toe blank in proper position in the upper as hereinafter described, and means for thereafter pressing the toe portion of the upper so supported, with the box-toe blank in position in the upper, so as to attach the blank to one or more adjacent layers of the upper.

For holding or supporting the last, the machine comprises an abutment 1 for the heel end of a last, a last pin 2 movably mounted and adapted to press a last 3 placed

thereon against the abutment 1 and a table 4 upon which the toe portion of the upper may be held while a box-toe blank is positioned upon it.

5 The last-heel abutment 1 is conveniently lined with felt or the like and is V-shaped, extending upwardly and at a small angle to the vertical from a base 5 which carries a standard 6 on which a lever 7 carrying the last pin 2 is pivotally mounted. The lever 7 carries the last pin pointing downwardly and forwardly on one of its ends, and the other end extends rearwardly of the pivot and is connected at 8 to a treadle (not shown) placed under the base. The pivot 9 of the lever 7 is horizontal and is surrounded by a spiral spring 10 which tends to move the last pin towards the abutment 1, the last pin being roughly parallel, in the position shown, to the line forming the apex of the V of the abutment. As shown in Figure 1, the last 3 held by the pin 2 and abutment 1 occupies a position bottom down with the toe portion pointing upwardly towards the operator. 25 The table 4 is supported by legs 11 upon the base 5 and is positioned at a small angle to the horizontal, so that the toe portion of an upper assembled on the last 3, but held at its rear end between the last and abutment 1, 30 may be turned backwardly over the table 4 and there held by the operator in his full view, inside uppermost, while the box-toe blank is being inserted as hereinafter described.

35 In using the machine the operator places an upper upon a last and depresses the treadle mentioned, thus lifting the last pin 2 away from the heel abutment 1. He then places the last upon the pin and releases the treadle. 40 Release of the treadle causes the last to be clamped between the pin and abutment with the forepart of the last closely under the table 4 and the tip line of the upper adjacent to the edge of the table. The toe portion 45 of the upper is then turned back upon the table and held there by one hand of the operator while the blank is inserted by the other hand, no manual holding of the last being required. A second depression of the treadle 50 at the conclusion of the use of the machine releases the last.

An upper as placed on its last generally comprises, besides the material composing the actual toe tip which will be visible when the 55 shoe is in wear, one or more layers of fabric of an absorbent nature. It will be assumed that the upper is of this kind and that these last-mentioned materials are attached together by stitches running across the toe tip 60 from side to side of the shoe near the tip line so that the rear edge of the visible toe tip overlaps the forward edge of the vamp of the upper; and it will be further assumed that the box-toe blank to be used is a composite one 65 made of two separate pieces, the one ther-

moplastic and the other of a heat resisting character, being made, for example, of fabric impregnated with a water soluble gum. A box toe blank of this kind and the method of making it are disclosed and claimed in application, Serial No. 19,160, filed in my name on March 28, 1925. In such a case it is usually desirable that the piece of gummed fabric should be accurately placed directly against the inside of the leather toe tip with its edge 70 closely abutting against the line of stitching; and the machine enables the position of this layer to be thus fixed with singular facility. Referring more particularly to Fig. 2, it will be seen that the upper of the shoe is so held that the rear edge of the toe tip 14 is adjacent to the rounded edge of the table 4 so that, if the toe tip is pressed down upon the table and the fabric layers 17, 18 pulled back, the toe tip is bent away from the forward 75 edge of the vamp 13 to provide a groove or pocket into which the operator may place the bottom or rear edge of the piece 15 which has been previously wet so as to be soft and pliable. 80

The thermoplastic piece may then be inserted while hot and soft and then the layers all secured together as usual by a mere wipe of the fingers or hand to press them firmly together and ensure adherence, but, as hereinafter indicated, the machine comprises a presser that may be used for this latter purpose. It will be apparent that the machine may be used in the manner described to incorporate in an upper any box-toe blank which 100 is sticky. In Figure 2, the portions 16, 17 and 18 represent respectively a lining proper not attached to the upper at the toe portion, and two layers of fabric, usually known as "doublers". 105

Dealing now with the aforementioned pressing arrangements of the machine of Figure 1, the presser 20 is mounted upon a stem 21 which can move up and down in a bore in a bracket member 22 slidably carried by a bar 23 which is adapted to slide horizontally in bearings 24, 25, carried at the upper ends of extensions 26, 27 of the standard 6. The rear end of the bar 23 is connected by a cord 28 to a second treadle, by depression of which the rod may be brought forwardly to the position shown against the pressure of spiral springs 29, 30 confined by collars 31, 32 fixed on the rod 23. Pivoted upon the bracket 22 at 33 is a bell-crank lever 34 slotted at its ends to engage pins 35, 36 fixed respectively upon the stem 21 and the bar 23. The bracket also carries a stop 37 for the lever 34. 110

Except when in use for pressing the toe portion of an upper the presser 20, bracket 22 and lever 34 occupy the positions indicated by the dotted lines 200, 220 and 340, the bar 23 being maintained in a rearward position by the springs 29, 30. By a pull upon the cord 28 the bar 23 moves forward carrying with 115 120 125 130

it the bracket 22 which is propelled by the spring 30 until it reaches the bearing 24. The bracket being thus stopped, further movement of the bar 23 and pin 36 causes rocking movement of the lever 34 into the position shown and causes depression of the presser 20 upon the table 4. The treadle by which the cord 28 is pulled is latched in position if it is desired to hold the presser down without action by the operator.

On release of the treadle, the springs 29, 30 expand, the action of the latter being to hold the bracket 22 in its forward position until the lever 34 contacts with the stop 37, the presser 20 being thereby raised from its pressing position before moving rearwardly, this latter movement being for the purpose of affording ample clearance for manipulation of the work on the table 4, it being understood that, in order to operate as hereinbefore described with reference to Figure 2, there should be abundant room above the table 4 for various layers such as 17, 18 to be turned back, the box-toe blank inserted, and the layers returned to position over the blank, all while the toe cap lies on the table 4. As shown, the presser 20 is so mounted and operated that the squeezing pressure is distributed uniformly over the blank; it may, however, be mounted so that the pressure is concentrated along the rear margin of the blank to secure the advantageous thinning of that margin by pressure upon the soft material of the blank, as in the press of the United States patent.

In addition to its pressing mechanism, the device of Figure 1 comprises an upper clamping finger adapted to clamp upon the top face of the table 4 at the rear margin thereof the extreme toe portion of the toe tip of the upper. Such a finger is shown at 40, extending from the hub of the lever 7, so that, as the last pin 2 moves toward the abutment 1 to clamp the last 3, the finger comes down towards the upper lying on the table. A stop pin 42 is provided to limit the upward movement of the spring 40 so that it does not interfere with the rearward movement of the presser 20.

The machine has been described above as provided with a presser 20, a last holder 2 and a clamping finger 40. It should be noted, however, that certain of these parts may be omitted or not used under certain circumstances without destroying the utility of the machine. For example, it may be desired to place a softened thermoplastic blank in an upper before the upper is assembled upon the last in which case the last holder is not required. In such case the toe portion of the upper may be placed upon the table 4 and held there by engagement of the clamp 40 with the toe tip while the operator inserts the softened blank in the upper.

The form of machine shown in Figures 3 and 4 is designed only for use in incorporat-

ing a box-toe blank in an upper which is already assembled upon a last. The pressing parts comprise a table 52 and a presser 50 which, as in the machine described in the patent referred to above, squeeze between 70 them the toe portion of the upper and the blank by reason of the descent of an arm 51 on which the presser is pivoted.

The machine comprises an extension from the base 53 of the press composed of two vertical ribs 55, spaced apart a convenient distance (about two inches) to support the cone of a last between them. The ribs 55 extend horizontally forward towards an operator of the press for about ten inches, their terminating in vertical front ends 56, the tops of the ribs being approximately on a level with the top of the table 52 of the press. The press and the ribs are mutually rigidly positioned, conveniently upon a common supporting bench or board to which all are united and which is cut away between the ribs so as to leave clearance for even a high upper to hang down between them. The top edges of the ribs are beveled off downwardly towards each other providing a V support for the cone of a last resting upon them. Further last holding means is provided by a last toe-end support mounted on the end of the presser-carrying arm 51 of the press. This support is composed of a wire 57, U shaped when viewed from above, with its ends attached to the arm and extending forwardly and downwardly therefrom towards the operator and the ribs.

In using the machine, the operator may place a last (on which an upper has been assembled) toe end upwards with the cone of the last between the front ends of the ribs as shown at the right in Figure 3, said ribs being beveled inwardly as shown in Figure 4. The substantially upright last thus supported rests against the chest of the operator so that the operator has both his hands free. He can then place a box-toe blank in correct position between the layers of the toe portion of the upper, as indicated by the arrow in Figure 3. Then, holding the upper at either side at the tip line, he will draw the upper towards the press, passing the toe portion of the upper, with the previously inserted box-toe blank, in between the presser and the table of the press and its tip line adjacent the edge of the table. In this movement the last necessarily follows the upper and travels sole upwards with its cone in the guideway between the ribs. As the toe end of the upper enters between the presser and the table, the toe end of the last engages the support 57, is lifted thereby, and is held, as shown, above the presser, the rear end of the last remaining supported on the ribs.

Where both a thermoplastic and a heat-resistant layer are used both must be rendered soft before such a pressing operation if the

press is unheated; but, if the press is heated and the heat-resistant layer is of fabric impregnated with a water soluble gum, advantage may be taken of the heating of the 5 press to facilitate fixing the gummed fabric layer in position in the upper, since the heat of such a press can soften such gummed fabric if the fabric is damped superficially.

Although the invention has been set forth 10 as embodied in particular machines, it should be understood that the invention is not limited in the scope of its application to the particular machines which have been shown and described.

15 The construction shown in Figs. 1 and 2 is not claimed specifically herein but forms the subject-matter of divisional application, Serial No. 149,490, filed Nov. 19, 1926.

Having thus described my invention, what 20 I claim as new and desire to secure by Letters Patent of the United States is:—

25 1. A machine for incorporating a stiffener in the upper of a shoe having, in combination, upper supporting means for facilitating the insertion of the stiffener by the operator, and means for pressing the stiffener into place.

30 2. A machine for incorporating a stiffener in the upper of a shoe having, in combination, a support for the upper constructed and arranged to permit the operator to use both hands to manipulate the layers of the upper and to insert a stiffener between selected layers, and means for pressing the stiffener into place.

35 3. A machine for incorporating a stiffener in the upper of a shoe having, in combination, means for facilitating the support of an upper so as to leave both hands of the operator free to manipulate the layers of the upper and to insert a stiffener between selected layers, and means for pressing the stiffener into place.

40 4. A machine for incorporating a stiffener in the upper of a shoe having, in combination, a table adapted to receive the toe portion of the upper, and means for supporting the upper in position to permit its toe portion to lie upon the table.

45 5. A machine for incorporating a box-toe blank in the upper of a shoe having, in combination, a table adapted to receive the toe portion of the upper, means for supporting the upper in position to permit its toe portion to lie upon the table, and means for pressing the toe portion including on inserted box-toe blank against the table.

60 6. A machine for incorporating a box-toe blank in the upper of a boot or shoe having, in combination, a table, means for supporting an upper assembled upon a last in position to permit the toe portion of the upper to lie upon the table, and means for pressing the toe portion including an inserted box-toe blank against the table.

7. A machine of the class described having, in combination, a press adapted to exert pressure upon a portion of the upper of a shoe, and a support adjacent to the press for holding an upper assembled upon a last in such manner that the manipulation of the layers of the upper and the insertion of a stiffener between selected layers of the upper prior to the pressing operation is facilitated. 70

8. A machine of the class described having, 75 in combination, a press adapted to exert pressure upon a portion of the upper of a shoe, and a support adjacent to the press for holding an upper assembled upon a last in such manner that the manipulation of the layers of the upper and the insertion of a stiffener between selected layers of the upper prior to the pressing operation is facilitated, said support being constructed and arranged to engage the last at two separated localities 80 during the pressing operation.

9. A machine of the class described having, 90 in combination, a press adapted to exert pressure upon a portion of the upper of a shoe, and a support carried by the frame of the press for holding a last with the upper assembled thereon in such manner that the manipulation of the layers of the upper and the insertion of a stiffener between selected layers, prior to the pressing operation, is 95 facilitated.

10. A machine of the class described having, in combination, pressing mechanism, and a support for an upper assembled upon a last, said support extending in front of the 100 pressing mechanism and having a recess to receive the cone of the last.

11. A machine of the class described having, in combination, a press adapted to fix a stiffener in position in the upper of a shoe 105 and a member adjacent to the press for supporting an upper assembled upon a last in two positions, a position in which the toe portion of the upper is accessible to the operator and a position in which the toe portion is engaged by the press.

12. A machine of the class described having, in combination, pressing mechanism including a table and a presser, a support for an upper assembled upon a last, said support having a guideway for the cone of the last extending toward the pressing mechanism so that a pull exerted on the toe portion of the upper in a direction to place said toe portion between the table and the presser 110 will pull the last along the guideway, and means for engaging the toe portion of the last during such movement and for holding it during the pressing operation.

13. A machine for incorporating a box-toe blank in the upper of a boot or shoe having, 125 in combination, a table and a member adapted to support an upper assembled upon a last adjacent to the table with the toe end of the last pointing upward and the toe por- 130

tion of the upper resting upon the table.

14. A machine for incorporating a box-toe blank in the upper of a shoe having, in combination, a table, a member adapted to support an upper assembled upon a last adjacent to the table with the toe end of the last pointing upward and the toe portion of the

upper resting upon the table, and means for pressing the toe portion of the upper against the table.

In testimony whereof I have signed my name to this specification.

FRED RICKS.
